CLAIM

The ornamental design for a vehicle mirror as shown and described.

DESCRIPTION

FIG. 1 is a front elevational view of a vehicle mirror, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front and left side perspective view thereof;

FIG. 8 is a bottom, front and left side perspective view thereof; and,

FIG. 9 is a top, rear and right side perspective view thereof. The claimed design is indicated by the relatively dark portions in the figures. The de-emphasized and relatively light portions form no part of the claimed design.

1 Claim, 9 Drawing Sheets
